UNITED STATES PATENT OFFICE.

JENNIE M. STEPHENSON, OF NEW HAVEN, CONNECTICUT.

WORK-HOLDER ATTACHMENT FOR SEWING-MACHINES.

SPECIFICATION forming part of Letters Patent No. 601,386, dated March 29, 1898.

Application filed June 17, 1897. Serial No. 641,169. (No model.)

To all whom it may concern:

Be it known that I, JENNIE M. STEPHENSON, of the city and county of New Haven, in the State of Connecticut, have invented a new and useful Improvement in Work-Holder Attachments for Sewing-Machines, fully set forth and described in the following specification, taken in connection with the accompanying drawings, which form a part thereof, and in which—

Figure 1 is a perspective view of my attachment secured to the table of a sewing-machine; Fig. 2, a bottom view of the table and frame, and Fig. 3 a detail view of the bag.

15 In all figures similar letters of reference represent like parts.

My invention relates to work-holders, and has for its object the production of a flexible work-holder adapted to be attached to a sewing-machine novel in construction yet light and durable.

In the drawings, A represents the table or bed of a sewing-machine, to the under side of which are secured sockets a'. A U-shaped frame B, formed of a metal rod, is adapted to have its ends fit into the sockets a' and bear against stops a², secured thereto, to hold said frame in position. A flexible bag C, of canvas or other suitable material, has a casing 25 formed near the upper edge of the front and sides thereof, so that it may be slipped onto the frame and hang therefrom, as shown in Fig. 1. The rear of said bag is slightly cut away at its ends, near the upper edge thereof, and loops of elastic or yielding fabric secured thereto, so that when said bag is in position on said frame said loops may be slipped over the ends of said frame and the rear of said bag brought into position with the sides there-

of. By reversing this operation the bag may 40 be easily reversed.

When the bag is on the frame B, the latter is attached to the machine by inserting the ends of the frame into the sockets, as described above. When the frame is so attached, the bag is brought in contact with the edge of the machine-table and the work operated upon is placed therein, being fed to or from the machine. All the material operated upon is thereby held within easy reach 45 50 of the operator at all times.

The frame may be attached to either the front or rear of the machine-table or to both sides, as the operator may desire, for the reception of the work as it is fed from the holder 55 to the machine, or vice versa.

Having now described my invention, what I claim, and desire to secure by Letters Patent, is—

In a work-holder, the combination with the 60 table of a sewing-machine; sockets a' secured to the under side of said table; a U-shaped frame B, the outer ends of which are adapted to fit into said sockets; stops a² against which the ends of the frame B abut; and a removable 65 flexible bag C, having a casing formed near the upper edge of the front, and sides thereof, while the rear of said bag is slightly cut away at its ends near the upper edge thereof; and elastic loops secured thereto, substantially as and for the purpose set forth.

In witness whereof I have hereunto set my hand this 10th day of June, 1897.

JENNIE M. STEPHENSON.
